UNITED STATES PATENT OFFICE

2,621,007

KNOCKDOWN STAND FOR CAMPING
AND PICNICS

Rene E. Barbin, Beverly, Mass.

Application August 21, 1948, Serial No. 45,455

2 Claims. (Cl. 248—125)

1

This invention comprises a novel article of camping or picnic equipment which is useful for supporting off the ground an assortment of articles, and for providing a convenient sectional table that may be readily adapted for the variety of conditions encountered in solitary camping or group picnicking in the woods or on the lawn or beach.

The article of my invention has an articulated frame which includes stakes that may be easily driven into the ground, and truss members connecting the stakes so as to form at the same time braces for the frame as a whole, and elevated beams or bridges from which may be suspended cooking utensils, receptacles for food or beverage, or any other articles that should be kept in safety and guarded against loss or ground dampness. For example, I provide cans of different sizes having hooks for connection with the truss members, hangers for kettles, and string bags with clips in which bottles of beverage may be suspended.

An important feature of my invention consists in a knock-down table made up of sector-shaped sections that are arranged to be mounted on one of the stakes at any convenient height and in size varying from a full disc or polygon to a single 45° sector.

Going more into detail, the table assembly of my invention may include a bracket having a circular or polygonal flange and each table sector may have a hanger shaped to hook over the flange and extend down inside it. Another element of the assembly is a locking member having a body of the proper size and shape to clamp the hooked portions of the table sections against the flange of the bracket. By loosening or moving this locking member to releasing position, the location and number of the table sections may be adjusted, and then by securing the locking member in operative position, all of the sections will be reliably locked in position for use.

These and other features of the invention will be best understood and appreciated from the following description of a preferred embodiment thereof, selected for purposes of illustration and shown in the accompanying drawings, in which:

Fig. 1 is a view in perspective of the complete article,

Fig. 2 is a view in cross-section through the table element,

Figs. 3 and 4 are views in elevation of an alternative table construction, and

Fig. 5 is a plan view partly in section on the line 5—5 of Fig. 4.

2

In its illustrated form the article comprises three sharpened stakes 10 which may be of metal, wood or colored plastic material. These are connected by truss bars 11, rectangular in cross-section and having a cylindrical boss or head at each end bored to receive one of the stakes 10 with a sliding fit. Each of the bosses is provided with a winged clamping screw 12 by which the truss bar may be adjustably secured to the stake at any desired height from the ground. The truss bars 11 are disposed edge-wise, that is to say, with their greatest dimension in a vertical plane, thus giving the truss maximum vertical stiffness.

Ordinarily the two truss bars will be disposed at substantially right angles and then driven into the ground in this position. The stakes are thus disposed in substantially triangular relation and maximum stiffness is imparted to the resulting frame. However, the number of stakes is of secondary importance and any stable arrangement of stakes and trusses like those herein described would be within the scope of the invention.

Upon one of the stakes 10, herein shown as the right hand stake of the group, is adjustably mounted a sectional table comprising a bracket 13 having a hub provided with a set screw 14 and an upstanding circular or polygonal flange 15. The bracket has a vertical bore in which the stake 10 may be received with a sliding fit and the bracket may be secured to the stake in any desired vertical position by the set screw 14.

The table itself, as herein shown, comprises four 90° sectors 16 having a shallow circumferential rib 17. To the inner end of each sector is secured a hanger 18 having a forked arm extending upwardly at right angles to the plane of the sector at its inner end. The arm is shaped to embrace the flange 15 of the bracket and to extend downwardly within the annular chamber of the bracket as best shown in Fig. 2.

A locking member having a circular flange 19 and an upstanding hub 20 is also bored to receive the stake 10 with a sliding fit. The flange 19 of the locking member is of such dimension as to engage and securely clamp the inner arms of the hangers 18 against the flange 15 of the bracket. After the locking member has been forced into position, it may be locked therein by a set screw 21 threaded into its hub 20. If desired, the locking member may be made of Vinylite or other plastic material of pleasing appearance. The locking member is effective to clamp securely in position a single sector of the table, or all the sectors thereof which form a table of 360° circumference. From the construction above

described it will be apparent that the table may be erected on any selected stake and fixed at any desired height thereon.

In addition to their bracing function, the truss bars 11 may be used to support such receptacles as the can 22, or the stockinet bag 23 shown in Fig. 1. Both of these articles are provided with hooks of the proper shape and size to engage the truss bars and thus may be moved to any convenient position thereon.

A modified table construction is shown in Figs. 3-5 comprising a circular flanged table or tray 22 having a hub 23 bored to receive one of the stakes 10 with sliding fit and having a set screw 24 by which it can be clamped to any selected stakes at the desired height. The hub 23 is shouldered to present a downwardly extending portion of reduced diameter that makes a sliding fit with the hub 25 of a stabilizing disc 26 having a series of downturned blades or prongs 28 struck from its body portion and turned downwardly. The stabilizing disc may thus be clamped to the hub of the table as shown in Fig. 3 and may be removed for service as a unit with the table. On the other hand, it may be employed as shown in Fig. 4 to stabilize and support the stake. For this function the set screw 27 is released, the hub 25 is slipped downwardly from the shouldered portion of the hub 20, and the disc dropped down the stake until it rests on the ground. In that position the prongs 28 may be driven into the ground by pressure of the foot upon the disc 26, and finally the disc may be secured in that position by turning the set screw 27. Having once planted and stabilized the stake in this manner, it will be apparent that the table or tray 22 may be conveniently removed from and replaced upon the stake for service purposes.

While the table or tray 22 and the stabilizing disc 26 are herein shown as secured to the stake 10 by set screws, it will be apparent that the means of attachment is of secondary importance and it would be within the scope of the invention to attach these members to the stake permanently or detachably by any desired means.

Having thus disclosed my invention and de-

scribed in detail illustrative embodiments thereof, I claim as new and desire to secure by Letters Patent:

1. An article of camping or picnic equipment comprising a supporting stake, a circular bracket having an upturned circumferential flange and being adjustably mounted on the stake, a series of complementary sector-shaped shelves each having an upstanding arm with a hooked portion 15 engaging said up-turned flange, and a locking member having an upstanding hollow hub fitting the stake and a circular body portion fitting within said upturned circumferential flange to clamp all of said hooked portions against the flange of the circular bracket.

2. An article of camping or picnic equipment comprising a supporting stake, a bracket adjustably mounted thereon and having an upstanding flange providing a central chamber, a table having hooked hangers engaging the flange of said bracket, and a locking member slideable on the stake into said chamber thus locking at diametrically opposite points said hangers within said chamber.

RENE E. BARBIN.
